UNITED STATES PATENT OFFICE.

AUGUST HASHAGEN, OF NEW YORK, N. Y., ASSIGNOR TO THE ALLIANCE VITRIFIED CHINA COMPANY, OF ALLIANCE, OHIO, A CORPORATION OF OHIO.

DESIGN FOR A PLATE OR SIMILAR ARTICLE.

Application filed February 7, 1928. Serial No. 25,251. Term of patent 3½ years.

To all whom it may concern:

Be it known that I, AUGUST HASHAGEN, a citizen of the United States, residing at New York, in the county of New York and State of New York, have invented a new, original, and ornamental Design for a Plate or Similar Article, of which the following is a specification, reference being had to the accompanying drawing, forming part hereof.

Figure 1 is a plan view of half of a plate showing my new design, it being understood that the ornamentation shown is continued throughout the entire plate; and

Figure 2 is an edge elevation of the plate.

I claim:

The ornamental design for a plate or similar article, as shown and described.

AUGUST HASHAGEN.
